UNITED STATES PATENT OFFICE.

JOHN W. KENNEDY, OF ROCHESTER, NEW YORK, ASSIGNOR TO THE SILL
STOVE WORKS, OF SAME PLACE.

DESIGN FOR A WATER-FRONT FOR STOVES.

SPECIFICATION forming part of Design No. 29,183, dated August 9, 1898.

Application filed July 18, 1898. Serial No. 686,290. Term of patent 14 years.

To all whom it may concern:

Be it known that I, JOHN W. KENNEDY, a citizen of the United States, residing at the city of Rochester, county of Monroe, and State 5 of New York, have invented and produced a new and original Design for Water-Fronts for Stoves and Ranges, of which the following is a specification, reference being had to the accompanying drawings, forming a part thereof.

10 Figure 1 is a perspective view of the water-front and Fig. 2 a plan view of the same.

The leading feature of my design is the general shape or configuration of the water-front, and particularly of the top and ends. 15 The upper face or panel 1 extends at a slight angle relative to the front face or panel 2, and the rear line of the panel 1 is substantially straight, as shown in Fig. 2, excepting at the ends, one of which has the rounding 20 corner extending into the recess 3 and upon the other end has steps 4 and 5 and the curved portion 6. The front panel 2 is curved slightly outward at 7 upon the right-hand end to meet an extended portion 8 of the face, which latter is rounded off upon its outer end 9, and

25 said rounded portion is also curved outward at the bottom to meet the small panel 10. Arranged upon the bottom of this panel is a flange 11, and at the top of the face 8 is a recess 12. Upon the end of the water-front are 30 the openings or apertures 13 and 14, and between them is the recess 15, having the inclined walls.

The left-hand end of the water-front extends slightly forward at 16 in a reverse curve 35 extending to the rear of the face 2 to meet the plane surface 17, arranged at a slight angle relative to the front 2. The outer edge of said plane is cut away upon the curve 18. A flange 19 projects from the lower end of the 40 portion 16, and beneath this is a curved recess 20. In the upper corner is a recess 21, having the rounded outer end.

What I claim is—

The design for a water-front for stoves and 45 ranges, substantially as shown and described.

JOHN W. KENNEDY.
